KORTING & MATHIESEN AKTIENGESELLSCHAFT, OF LEUTZSCH, GERMANY.

TRIMMING-INDICATOR FOR ARC-LAMPS.

1,159,920.

Specification of Letters Patent.

Patented Nov. 9, 1915.

Application filed July 26, 1913. Serial No. 781,333.

To all whom it may concern:

Be it known that I, RICHARD FRETZDORFF, a subject of the German Emperor, residing at 2 Carolastrasse, Leutzsch, near Leipzig, 5 Germany, have invented a new and useful Trimming-Indicator for Arc-Lamps, of which the following is a specification.

According to this invention an arc lamp is provided with a visual indicator associated with means for holding it in one position and means moving as the carbon holder moves for releasing the indicator at a predetermined interval before the carbon is completely consumed, mechanism being also 10 provided whereby the setting of the carbon holder on the introduction of a new carbon will restore the indicator to normal position.

The invention is illustrated in the accompanying diagrammatic drawings, in which—

Figures 1 and 2 are similar views taken at right angles to each other and show the preferred form of mechanism.

The base of the lamp is indicated at 19, 25 the cap at 20 and a chain wheel at 21. A rod, 22, is connected by the chain 34 to the upper carbon holder.

23 is a finger carried by the rod 22 and for the purpose of adjusting its height it is 30 provided with a slot 33 and a binding screw 32.

25 is a bracket provided with a slot through which a notched link 24 passes; 26 is an indicator fast on a shaft 27 and 28 is 35 a crank arm also fast with it, the link 24 being connected to the end of the arm 28 while its notch engages the bracket 25 when the indicator 26 is in its normal position.

29 is a lever arm fast with the shaft 27. 40 30 is the upper carbon carrier and 31 is an upwardly inclined arm on it projecting into the path of the lever 29.

When, owing to the consumption of the upper carbon, the rod 22 rises, its finger 23 45 will in time trip the link 24 and the indicator 26 will fall into the dotted position turning the shaft 27 and the parts carried by it, the lamp continuing to burn as usual.

When the trimmer replaces a carbon he necessarily raises the carrier 30 and the arm 50 31 will act upon the arm 29 and so bring the indicator 26 into its normal position in which it will be locked by the notch on the arm 24 engaging with the bracket 25.

The invention is not limited to any particular type of arc lamp or to any particular method of carbon feed. 55

What I claim is:—

1. In an arc lamp the combination of a moving carbon holder, a visual indicator, 60 means for holding it in one position, means moving as the carbon holder moves for releasing the indicator from that position at a predetermined interval before a carbon is completely consumed, and means whereby 65 the setting of the carbon holder on the introduction of a new carbon restores the indicator to that position.

2. In an arc lamp the combination of a visual indicator fast on a shaft, a crank arm 70 on said shaft, a link carried by the said arm, means for locking said link and means moving as the carbon is consumed for acting on the link.

3. In an arc lamp the combination of a 75 moving carbon holder, a visual indicator fast on a shaft, a lever arm on said shaft, a crank arm on said shaft, a link carried by said crank arm, means for locking said link, means moving as the carbon is consumed 80 for acting on the link and means connected to the carbon holder adapted when the carbon is being set to act on the lever arm after the indicator has been operated to move the shaft and the parts carried by it to their 85 original position.

RICHARD FRETZDORFF.
